CLAIM

The ornamental design for an automobile tire, including the peripheral boundaries of the claimed surfaces, as shown and described.

DESCRIPTION

FIG. 1 is a front view of the automobile tire of the invention; FIG. 2 is a rear view thereof;

FIG. 3 is a left-side view thereof;

FIG. 4 is a right-side view thereof;

FIG. 5 is an enlarged fragmentary right-side view thereof; and,

FIG. 6 is an enlarged end elevational view of the section 6 in FIG. 5, taken along the line 6A—6B in FIG. 5.

The broken line showing of portions of the automobile tire is for illustrative purposes and forms no part of the claimed design.
